Primary Examiner — Garth Rademaker*Assistant Examiner* — Salamah Jordan(74) *Attorney, Agent, or Firm* — Kilpatrick Townsend & Stockton LLP(57) **CLAIM**

The ornamental design for a gaming wheel base, as shown and described.

DESCRIPTION

FIG. 1 is a front, left side perspective view of a gaming wheel base, shown with environmental wheel in use, showing our new design;

FIG. 2 is a rear, right side perspective view thereof, shown with environmental wheel in use;

FIG. 3 is a front, left side perspective view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a left side elevation view thereof; and,

FIG. 9 is a right side elevation view thereof.

The broken lines shown in the drawings are included for the purpose of illustrating portions of the gaming wheel base that form no part of the claimed design.

The broken lines on the wheel and FIGS. 1 and 2 are included for the purpose of illustrating environmental subject matter and form no part of the claimed design
